INVENTOR.
Howard R. Newland

BY

Geo. P. Hinman, ATTORNEY.

UNITED STATES PATENT OFFICE.

HOWARD R. NEWLAND, OF BENS RUN, WEST VIRGINIA.

PIPE WRENCH.

Application filed March 30, 1923. Serial No. 628,738.

To all whom it may concern:

Be it known that I, HOWARD R. NEWLAND, a citizen of the United States, residing at Bens Run, in Pleasants County, and State 5 of West Virginia, have invented certain new and useful Improvements in Pipe Wrenches, of which the following is a specification.

This invention relates to wrenches of the class adapted to grasp and firmly hold relatively large objects, such as well casings and the like, and has for one of its objects to improve the construction and increase the efficiency and utility of device of this character.

Another object of the invention is to provide a device of this character which may be operated in either direction without structural change and which may be readily adapted to pipes, rods or similar structures 20 of various diameters.

With these and other objects in view the invention consists in certain novel features of construction as hereinafter shown and described and then specifically pointed out 25 in the claims, and in the drawing illustrative of the preferred embodiment of the invention—

Figure 1 is a plan view, partly in section, of the improved implement.

Figure 2 is a side elevation.

Figure 3 is a side elevation of the main stock detached.

Figure 4 is an enlarged detail illustrating the construction of the joint between the 35 outer and inner jaw members.

The improved implement comprises a stock represented as a whole at 10 and formed with a socket 11 in the ends to receive turning handles 12 and with an intermediate slot 13 therethrough, as shown.

The improved implement includes two sets of coacting jaw devices which for the purpose of this description are referred to as the outer and inner jaws.

The inner jaws are represented at 14 and 15 reversely curved and pivoted at 16 and 17 in the slot 13, the jaws 14 and 15 being provided respectively with reversely inclined pipe engaging teeth 18 and 19. The stock 10 and the jaws 14 and 15 are provided with a plurality of apertures for the pivots 16 and 17, to enable the inner jaw devices to be adjusted nearer to each other and the lengths of the jaws controlled, to 55 enable them to fit larger or smaller pipes or other objects, as shown in Figure 1.

At their outer ends the inner jaws 14 and 15 are formed respectively with spaced ears 19 and 20 between which reduced portions 21 and 22 on the inner ends of the outer 60 jaw members 23 and 24 are pivoted at 25 and 26. The outer jaw members are provided with reversely inclined pipe engaging teeth 27 and 28 corresponding to the teeth 18 and 19 of the inner jaws.

Swinging at one end at 29 upon the outer end of the outer jaw 23 is a link device 30, the opposite end of the link being coupled at 31 to nut device 32 movable upon the outer curved face of the outer jaw 24.

The outer end of the outer jaw 24 is formed with an outwardly projecting head 33 against which a straining bolt 34 engages, the bolt operating through the nut 32 and provided with a turning head 35. The pipe 75 is indicated by dotted lines at 36, and against which the teeth of the jaw members engage as indicated in Figure 1.

The improved implement is designed more particularly for use in handling the casings of oil or like wells, and may be employed with equal facility for screwing the sections of piping together or unscrewing them, by merely reversing the direction of movement of the operating handles 12.

When the implement is to be applied the bolt 34 is released and the link 30 with its nut 32 and the bolt 34 turned over the jaw member 23 and the jaws separated to permit the implement to be disposed around the 90 pipe 36. The link 30 is then restored to the position shown in Figures 1 and 2 and strain applied by actuating the bolt 34 to cause all the teeth to firmly grip the pipe.

If the pipe is to be screwed upon another section the handles 12 will be moved to the right and the teeth 18 and 28 will engage the pipe and rotate it to the right while the teeth 19 and 27 move idly over the pipe. If on the other hand the pipe is to be unscrewed, the handles 12 will be turned to the left and the teeth 19 and 27 will grip the pipe and turn it to the left, while the teeth 18 and 28 move idly over the pipe.

Thus the pipe can be turned in either direction by merely reversing the motion of the handles 12.

It will be noted that the portions of the outer jaws 23 and 24 externally of the reduced portions 21 and 22 are bevelled, as shown at 37 and 38, to limit the outer and inner movement of the jaws 23 and 24 rela-

tive to the jaws 14 and 15 and thus prevent abnormal outward movement between the jaws.

The improved implement is simple in construction, is constructed wholly of metal and as strong as necessary, and may be constructed of any size or capacity.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described the invention what is claimed as new is:

1. A wrench device comprising a stock adapted to support a lever handle, inner jaw

devices swinging from said stock, outer jaw devices swinging from said inner jaw devices, a link member swinging at one end to one of said outer jaw devices, and means carried by the link member cooperating with the other outer jaw device to produce strain longitudinally of said link member.

2. A wrench device comprising a stock adapted to support a lever handle, inner jaw devices swinging from said stock, outer jaw devices swinging from said inner jaw devices, a link member swinging at one end to one of said outer jaw devices, a nut device engaged by said link member, and a clamp screw engaging said nut and bearing against the other outer jaw member.

In testimony whereof, I affix my signature hereto.

HOWARD R. NEWLAND.
